UNITED STATES PATENT OFFICE.

EDWARD W. ISOM, OF WINNETKA, ILLINOIS, AND JOHN E. BELL, OF BROOKLYN, NEW YORK, ASSIGNEES TO SINCLAIR REFINING COMPANY, OF CHICAGO, ILLINOIS, A CORPORATION OF MAINE.

CONDENSER.

Application filed May 19, 1921. Serial No. 470,790.

To all whom it may concern:

Be it known that we, EDWARD W. ISOM and JOHN E. BELL, citizens of the United States, residing, respectively, at Winnetka, county of Cook, and State of Illinois, and Brooklyn, county of Kings, and State of New York, have invented certain new and useful Improvements in Condensers, of which the following is a specification.

10 Our invention is designed more particularly for use in condensing vapors from oil stills, though it will be apparent from the following description taken with the drawings that it is of general application for condensing vapors of liquids other than oil. The usual practice of condensing distillates from oil stills is to pass them through tubes or other passages which are cooled by means of air, water, or other fluid applied to the outer surfaces thereof. In our improved condenser, however, the vapors are injected into a body of the condensate from such vapors which is maintained at a suitable temperature by circulating streams of the body of such liquid into contact with cooling means and returning them to the main body. In the accompanying drawings we have shown and in the following specification described a preferred form of the invention. It will be understood, however, that the specific disclosure is for the purpose of exemplification only and that the scope of the invention is defined in the following claims in which we have endeavored 25 to distinguish it from the prior art so far as known to us without however relinquishing or abandoning any portion or feature thereof.

In the drawings Fig. 1 is a plan view of our improved condenser, and Fig. 2 is a vertical central section thereof, parts being shown in elevation.

In the preferred form of the invention shown the main body of the condensate is contained in a tank 5 of cylindrical shape with convex top 6 and bottom 7. It is designed to maintain this tank nearly but not quite full of condensate, a space being left above the liquid for the fixed gas, a considerable proportion of which is ordinarily developed, particularly in distillation under

pressure or cracking. At 8 we have shown a connection to provide for the escape or withdrawal of the fixed gases, which may be connected to a gasometer or to means by which the pressure of the gas may be regulated. The pressure may be either above or below atmospheric, depending upon the desired method of operation. At 9 is shown a gauge-glass for observing the level of the liquid in the tank, the surface of which is maintained preferably within the limits of the glass.

Provision is made for cooling the condensate by circulating it through a series of coolers outside the tank proper. In the preferred form of the invention shown there are eight of these coolers 10 equally spaced about the drum or tank, each comprising a cylindrical body 12 in communication with the tank towards its upper end by a connection 11 and towards its lower end by an elbow-connection comprising the horizontal pipe 13 and the vertical pipe 14. The coolers 10 comprise headers 15, 16 arranged respectively at their upper and lower ends, one of the headers being adapted for connection to some source of cooling fluid, water, or if it is desired to preheat the oil for the still, the latter may be used as a cooling fluid. The other header may be connected either to waste or to a receptacle for the liquid which has been used for cooling purposes. The headers are provided respectively with the connections 17, 18 and are connected by the cooling tubes 19 through which the cooling liquid or fluid flows from one header to the other. It will be observed that the space about the cooling tubes is in communication with the tank and the contents of the latter are free to flow therethrough. In order to induce the circulation of the liquid through the coolers the vapors coming from the still are introduced at 20 in each elbow-connection between pipes 13, 14 and in the direction of the latter pipe. The injection of the vapors and such fixed gases as they contain in this manner and under the pressure at which they come from the still causes an injector action in the pipe 14 which has the effect of drawing the condensate from the cooler, so that there is a

continuous and rapid circulation of liquid from the tank through the connection 11, the cooler, and the pipes 13, 14. The pipe 14 in each instance is provided with or connected to a nozzle 21 having a reduced end and over said reduced end is arranged a series of frustro-conical deflectors 22, 23, 24, which are secured in spaced relation in any suitable manner so as to leave between them 10 passages for the liquid in the tank. The vapor and liquid issuing from the nozzle 21 therefore draws in the liquid between the deflectors and mixes it with the vapors and liquid coming through the nozzle 21. Provision may be made for drawing off the condensate at any desired point but we prefer to provide for this purpose a draw-off 26 at or near the level at which it is proposed to maintain the condensate. It is also desirable to provide draw-off openings at 20 points where any heavier matters contained in the condensate are apt to collect, and for this purpose we have shown a draw-off 27 at the bottom of the tank and draw-offs 28 25 near the bottoms of the respective coolers.

From the foregoing the operation of our improved condenser will readily be understood. The injection of the vapors under high pressure at 20 causes a rapid circulation of the liquid from the tank through the respective coolers, reducing the temperature of the condensate so that when it is mixed with the vapor entering through the pipe 20 it is in suitable condition to rapidly condense the vapor. The mixture of vapor and condensate rising through the pipe 14 and nozzle 21 and issuing through the latter and through the conical deflectors causes a corresponding series of eddy currents in the tank which bring additional quantities of fresh condensate directly in contact with the vapors issuing through nozzle 21, further cooling the vapors so that they are thoroughly condensed and 40 only the non-condensable fixed gases escape through the surface of the condensate and into the space about the same. The pressure above the condensate may be maintained at any point desired, whether above 45 or below atmospheric, by suitably controlling the exhaust of fixed gases from the tank.

We claim:

1. In an apparatus for condensing vapors, 55 a closed tank adapted to contain the condensate thereof, a cooler, a pair of connections between the cooler and the tank to provide a closed circulation from the tank through the cooler and back to the tank, 60 means for injecting the vapors below the normal liquid level in said tank, and means for withdrawing condensate from the tank.

2. In an apparatus for condensing vapors, 65 a closed tank adapted to contain the condensate thereof, a cooler, a pair of conn-

nections between the cooler and the tank to provide a closed circulation from the tank through the cooler and back to the tank, means for injecting the vapors below the normal liquid level in said tank in admixture with the condensate from the cooler, and means for withdrawing condensate from the tank. 70

3. In an apparatus for condensing vapors, 75 a closed tank adapted to contain the condensate thereof, a cooler, a pair of connections between the cooler and the tank to provide a closed circulation from the tank through the cooler and back to the tank, means for injecting the vapors into this 80 circulatory path to cause forced circulation therein, and means for withdrawing condensate from the tank.

4. In an apparatus for condensing vapors, 85 a closed tank adapted to contain the condensate thereof, a cooler, a pair of connections between the cooler and the tank to provide a closed circulation from the tank through the cooler and back to the tank, means for injecting the vapors in concurrent flow with the condensate from the cooler into the tank, and means for withdrawing condensate from the tank. 90

5. In an apparatus for condensing vapors, 95 a closed tank adapted to contain the condensate thereof, a cooler, a pair of connections between the cooler and the tank to provide a closed circulation from the tank through the cooler and back to the tank, means for injecting the vapors into the circulating condensate, means for injecting the resulting mixture into the tank below the normal liquid level, and means for withdrawing condensate from the tank. 100

6. In an apparatus for condensing vapors, 105 a closed tank adapted to contain the condensate thereof, a cooler adjacent thereto, an upper connection between the tank and the cooler below the normal liquid level, a tube entering the tank below this upper connection, means for injecting the vapors, a lower connection between the cooler and this tube, and means for withdrawing condensate 110 from the tank.

7. In an apparatus for condensing vapors, 115 a closed tank adapted to contain the condensate thereof, a cooler adjacent thereto, upper and lower connections between the tank and the cooler for permitting a circulation of liquid from the tank through the cooler and back to the tank, means for injecting vapors to be condensed into the circulating liquid, means for introducing the resulting mixture into the main body of liquid in the tank, and means for withdrawing condensate from the tank. 120

8. In an apparatus for condensing vapors, 125 a closed tank adapted to contain the condensate thereof, a cooler a pair of connections between the cooler and the tank to 130

provide a closed circulation, means for injecting the vapors to be condensed into the circulating condensate and means for injecting the resulting mixture into the tank below the normal liquid level, said last mentioned means comprising injectors for entraining and admixing an additional amount

of condensate with the mixture before it is discharged into the main body of liquid, and means for withdrawing condensate from the tank.
